INDEXING MECHANISM

Daniel V. Waters, Lebanon, N. J., assignor to
 Western Electric Company, Incorporated, New
 York, N. Y., a corporation of New York

Application September 27, 1951, Serial No. 248,503

1 Claim. (Cl. 74—155)

1

This invention relates to indexing mechanism and more particularly to mechanism for indexing a unit pre-determined distances intermittently for locating the unit at given successive positions and locking it against movement during rest intervals.

Many types of indexing mechanisms have been employed to intermittently move or rotate a unit pre-determined distances but due to the ever existing lost motions resulting from the inaccuracies of the manufacture of the parts of such mechanisms, together with variations in their movements due to wear, there is little assurance that such mechanisms will move their units exactly the required distances and hold them against displacement during the intermediate rest intervals.

It is the object of the present invention to provide an indexing mechanism which is simple in structure, readily actuatable and highly efficient and accurate over a long period of service.

With this and other objects in view, the invention comprises an indexing mechanism for a unit mounted for rotation about an axis including a member mounted concentric with the axis with spaced notches in its periphery and connected to the unit for rotary movement therewith. A latch, normally actuatable to secure the member against movement and to accurately locate the unit in known positions, is released by a cam which functions to actuate a pawl subsequent to the releasing of the latch to move the member with the unit a given distance.

In the present embodiment of the invention, the latch is provided with a cam roller positioned to ride on the outer surface of the cam to release the latch from its member and adapted to be located in a groove of the cam to permit return movement of the cam while the latch remains in its holding position. A door, normally closing the exit end of the groove, may be opened by the cam roller during the return movement of the cam to allow the roller to leave the groove. When closed the door will complete the outer cam surface over which the roller rides during actuation of the cam to release the latch.

Other objects and advantages will be apparent from the following detailed description when considered in conjunction with the accompanying drawings wherein:

Fig. 1 is a front elevational view of the mechanism;

Fig. 2 is a fragmentary isometric view of the latch and actuating cam; and

Fig. 3 is a fragmentary front elevational view

2

of the mechanism illustrating the return movement of the cam and pawl.

Referring now to the drawings, let it be understood that in the present embodiment of the invention, the indexing mechanism is to move a unit 10 pre-determined distances about its axis.

The unit 10 is mounted on a shaft 11 which is journaled in any suitable bearings not shown. A member 12 fixedly mounted on the shaft 11 has 10 equally spaced notches 14 in its periphery providing shoulders 15 for engagement with a pawl 16. The pawl 16 is pivotally supported at 17 on an arm 18 which is mounted for free movement on the shaft 11 between stops 19 and 20. A suitable 15 spring 21 normally urges the pawl 16 counterclockwise so that it will ride on the periphery of the member 12 and enter the successive notches 14.

The member 12 has a circular arrangement of 20 arcuate members 23 spaced from each other so that their tapered ends 24 provide recesses 25 to receive a wedge shaped portion 26 of a latch 27. The latch 27 is mounted for movement on a fixed support 29 and normally urged clockwise by a 25 spring 30. A cam roller 32 rotatably mounted on the opposite side of the latch 27 from the portion 26 is positioned to ride on surfaces 33 and 34 of a cam 35. The cam 35 is freely mounted on the shaft 11 and is provided with an arm 36 which is pivotally connected at 37 to a yoke 38. The yoke 38 is mounted on the upper end of a piston rod 39 of an air cylinder 40 which is mounted on a 30 fixed position pivot 41. In the present embodiment of the invention, projection 42 of the yoke 38 is positioned to engage and actuate a microswitch 43 mounted at a fixed position and adapted to control a solenoid valve to bring about reverse movement of the air cylinder and the indexing mechanism.

40 The cam 35 has radially extending surfaces 45 positioned within a yoke portion 46 of the lever 18 with suitable space 47 for lost motion to permit movement of the cam 35 a given distance sufficient to release the latch 27 prior to movement of the lever 18 a distance sufficient to cause 45 its pawl to move the member 12.

The cam 35 has a groove 50 formed in one side 50 thereof for the cam roller 32 to enter as the cam completes its movement in a counter-clockwise direction. A door 51 of the contour shown is pivotally supported at 52 and adapted to close the exit end of the groove 50. The lower edge of the door 51 is tapered at 53 to conform to the adjacent surface of the groove and its outer surfaces lie in planes with the adjacent outer surfaces of

the cam to complete these surfaces over which the roller 32 rides.

Considering now the operation of the indexing mechanism, let it be assumed that at desired intervals of time, a solenoid valve is operated in one direction to cause air under pressure to be directed to the top of the air cylinder 40 to move the piston rod 39 downwardly. The first portion of this movement causes the cam 35 to rock about the shaft 11 to engage the cam roller 32 to move the latch 27 about its pivot 29 moving the wedge shaped portion 26 free of the adjacent notch 25. This occurs prior to the engagement of the pawl 16 with the adjacent shoulder 15. The lost motion portion 41 of the yoke 46 and that existing between the end of the pawl 16 and the adjacent shoulder 15, allows sufficient time for the cam to release the latch. Continued movement of the ram 39 downwardly will cause the cam 35 to move the lever 18 counter-clockwise causing the pawl 16 to move the member 12 a given distance determined by the stop 20. During the counter-clockwise travel of the cam 35, the latch 27 is moved outwardly while the roller is traveling over the surface 33 and the closed door 51. The latch is held outwardly while riding over the cam surface 34, but when this surface travels beyond the roller 32, the latch will be free to move inwardly so that the projection 26 may ride on the outer surface of the adjacent arcuate member 23 and enter the next notch 25 when brought into position. The tapered ends of the arcuate members 23 and the corresponding tapered walls of the wedge-like member 26 assure accurate positioning of the member 12 with the unit 10 and locking of the member and unit against movement during the rest interval of the indexing mechanism.

The completion of the first half of the operating cycle of the mechanism during downward movement of the ram 39 completes the indexing of the unit 10 and the actuation of the switch 43 to operate the solenoid valve, to direct air under pressure to the bottom of the air cylinder 40 to move the ram 39 upwardly. This action of the ram rotates the cam 35 clockwise and during this movement, the latch 27 is in its holding position with the groove 56 providing a by-pass for the roller 32, leaving the latch undisturbed. The door 51 would normally close of its own weight but may be provided with a spring or other suitable means if so desired to nor-

mally move the door into its closed position. The slanting position of the door with respect to the cam roller 32, will tend to aid the spring 30 in forcing the latch into its holding position as the cam travels clockwise relative to the latch. This movement of the cam returns the lever arm 18 to its normal position against the stop 19 and in so doing, moves the pawl 16 into registration with the next notch 14 ready for the next intermittent movement of the unit 10 through operation of the indexing mechanism.

Although the various elements of the indexing mechanism are not complicated in structure and do not require delicate machining, these elements assure accurate movement of a unit known measured distances and the locating and locking of the unit at these chosen positions during each operating cycle of the mechanism.

It is to be understood that the above described arrangements are simply illustrative of the application of the principles of the invention. Numerous other arrangements may be readily devised by those skilled in the art which will embody the principles of the invention and fall within the spirit and scope thereof.

What is claimed is:

An indexing mechanism for a unit mounted for rotation about an axis, the mechanism comprising a member mounted concentric with the axis with spaced notches in its peripheries and connected to the unit for rotary movement therewith, a latch, normally actuatable to engage the member to secure it against movement, having a projection thereon, an oscillating cam having an outer surface to engage the projection and disengage the latch from the member, a groove having an outlet to serve as a by-pass for the projection during the return movement of the cam and a door for the outlet providing a part of the outer surface for the cam, normally closed and actuatable into open position by the projection, and a pawl movable by the cam to enter an adjacent notch in the periphery of the member to move the member subsequent to the releasing of the latch.
